UNITED STATES PATENT OFFICE.

ALEXANDER D. CLARKE, OF OMAHA, NEBRASKA.

AMALGAMATING APPARATUS.

SPECIFICATION forming part of Letters Patent No. 247,484, dated September 27, 1881.

Application filed April 8, 1881. (No model.)

To all whom it may concern:

Be it known that I, ALEXANDER D. CLARKE, of the city of Omaha, county of Douglas, in the State of Nebraska, have invented certain 5 new and useful Improvements in Amalgamating Apparatus, of which the following is a specification.

This invention relates to an apparatus for amalgamating the fine gold found in alluvial 10 deposits, and to an apparatus for use in operating the same.

It consists in the novel construction and arrangement of devices hereinafter set forth and claimed.

15 The details of my invention will be fully understood from the drawings accompanying this specification and forming a part thereof, and whereof—

Figure 1 is a side elevation, and Fig. 2 is a 20 longitudinal vertical section, of my improved amalgamator. Fig. 3 is a partial side elevation, showing a modification of a part of the device. Fig. 4 is a cross-section of the screening apparatus. Fig. 5 is a cross-section of the 25 mercury-holding cylinder used in the modification shown in Fig. 3, and Fig. 6 is an exterior view of the same, both these views being considerably enlarged.

A represents a series of inclined graduated 30 screens, placed one above the other, with the coarsest at the top and finest at the bottom, all mounted upon pivoted standards A', so they may be rocked or oscillated for the purpose of agitating the earth, which is thrown in the first 35 instance upon the top one. Each screen is open at the lower edge for the discharge of such portions of the material as cannot fall through their apertures. Under the lower screen is a level imperforate surface, A², inclosed at all 40 sides, except over the funnel or hopper B. To this surface A² only the finer portions find their way, and as they issue therefrom they fall into said funnel, and there they meet a blast from the chamber C, in which compressed air is 45 stored, as said blast passes from the chamber C through the conduit B'. By this conduit the sand or earth is conducted to another funnel, D, suspended with its apex opening within a close chamber, D'. Another and principal 50 blast is conducted from the chamber C to the interior of this chamber D' by one or more pipes C'. By the united blasts the earth is

driven from the chamber D' through a funnel, D², located in the bottom thereof, so that it impinges with considerable force upon the mercury-holding agent already mentioned. Several kinds of agents may be employed for this purpose, and they may vary considerably in character; but they may all be described in general terms as porous substances, and as holding the 60 mercury in their pores. One material that I employ for this purpose is wood, which is so charged with the mercury that the latter permeates and occupies its pores in every portion. When a block of wood, E, thus charged with 65 mercury is placed upon the shelf E' directly under the blast as it issues from the chamber D', the result will be this: The wood itself will be worn gradually away under the attrition of the particles of sand, and this wearing away 70 is continually bringing to exposure and freedom fresh portions of mercury, which take up the valuable metal in the blast, and as sufficient quantities are thus uncovered they coalesce and form drops and run off or are blown 75 off by the force of the blast into a trough or other suitable device for collecting the same.

Instead of wood, other porous substances which will wear away under the action of the sand in the blast so as continually to expose 80 fresh mercury substantially in the same way as does the wood may be substituted for it. Among these materials may be mentioned paper, stone, earthenware, and glass.

I sometimes jet the blast against a porous 85 diaphragm or fabric—such as buckskin—which is being constantly charged with mercury from a body thereof upon the reverse side of the fabric. The manner in which this is done appears in Figs. 3, 5, and 6, wherein F represents a tube closed at one end, and containing a body of mercury, which is being continually replenished from an upright pipe, F', at the open end of the tube and opening into it. At one side the tube F is cut away, so as to expose 90 a diaphragm, F², of buckskin, which covers the opening, and through the pores of which the mercury from within the tube constantly oozes or percolates. The tube being placed upon the shelf so that the blast strikes the 95 opened side, I obtain a result similar to that attending the use of the charged wood, with the exception that the supply of mercury will 100 probably be somewhat more liberal, as a thin

skin or fabric will permit the passage of a considerable amount. If a single thickness of buckskin does not sufficiently restrain the percolation, additional thicknesses may be used, and in Fig. 5 I have illustrated the tube as provided with two thicknesses and an intermediate layer of felt or sponge, F³. It may be easier to make the skin to conform to the entire interior of the tube rather than to make it cover the opening simply. The exterior bands, f, prevent the bulging of the diaphragm under the pressure of the mercury from within.

The shelf is adjustable upon the standard E², adjoining the pipe C', as to height, by means of the thumb-screw e². It may also be adjustable to and from the standard, if that is thought desirable.

Such portions of the blast as have no affinity for the mercury or do not come in contact therewith, and also the combined particles of gold and mercury, pass beyond into a casing, G-G', where they come in contact with a series of amalgamating-plates, H, and if they pass them also, they are secured below in the trough H'. Another and larger shelf, H², extends from this casing under the shelf E', so as to catch such of the mercury and gold as may drop from the shelf E', and also such particles as may shoot past the edge of the mercurial holder. Exit is given from the casing G-G' at the lower outer end or at any other proper point for the air.

The tube F may, of course, be of any convenient conformation or size, as its function is that of a reservoir. The diaphragm should be of such a nature as not to wear rapidly away under the attrition of the blast, and I recommend that when the mercury is fed from a reservoir through a diaphragm the blast be not too strong, because of the freedom with which the mercury is supplied by that method.

The apparatus I have shown may be used also in wet mining, and also in treating the fine product of stamp-mills; but I recommend, where the material to be operated upon is wet, that the mercurially-charged wood or its equivalent be used instead of the buckskin and the body of mercury back of it.

Great economy in the amount of mercury and a thorough commingling of the mercury and the mineral are important beneficial features of my invention.

In the use of the apparatus it is only necessary that the earth in a comminuted state be delivered to the embrace of the blast, and by

it be thrown directly upon the mercury-holding material or agent, substantially as set forth, and hence the construction of the apparatus becomes comparatively immaterial. The construction shown, however, is excellently adapted to serve the purposes of the invention.

The blast through the pipe B' is primarily intended to elevate the mineral to a convenient height to subserve and render easy the balance of the operation, and hence need not be very strong, and it may be regulated in any convenient way.

If found desirable, hoods may be applied at the open places above and below the chamber D', to prevent loss of material or in the power of the blast.

Inasmuch as the essence of the invention lies in the violent projecting of the auriferous earth against a porous substance charged with mercury, as above described, I do not wish to be limited in my claim to an air-blast, as it is obvious that a steam, or water, or steam and air, or water and air blast will perform the same function as the air alone, and in some cases they may be preferable, because they moisten the material.

My apparatus may be used in the amalgamation of any of the precious metals.

I have described two methods of supplying the mercury—viz., one by the use of a porous body holding the mercury in its pores, and from which it is released by the wearing action of the blast, and another by feeding the mercury to the blast from a reservoir through the pores of a diaphragm. Any claim which I am entitled to make to the former of these I reserve for a subsequent application.

I claim—

1. The combination of apparatus for conducting the blast for jetting the mineral, and a diaphragm of porous material which receives the jet, and is provided with a reservoir for keeping it charged with mercury, substantially as set forth.

2. The combination of the following elements: the screening apparatus, the blast-conducting devices, the conduit for conducting the mineral material, the mercurially-charged porous substance, and a support for the same, and the collecting plates and trough, substantially as specified.

ALEXANDER D. CLARKE.
